UNITED STATES PATENT OFFICE.

JOSEPH BREZIN, OF PHILADELPHIA, PENNSYLVANIA, ASSIGNOR OF ONE-THIRD TO HIMSELF, ONE-THIRD TO LOUIS BERZON, AND ONE-THIRD TO WILLIAM KOSAKOFF, ALL OF PHILADELPHIA, PENNSYLVANIA.

BAG-FRAME LOCK.

Application filed September 22, 1921. Serial No. 502,336.

To all whom it may concern:

Be it known that I, JOSEPH BREZIN, a citizen of the United States, residing at Philadelphia, county of Philadelphia, and State of Pennsylvania, have invented a new and useful Improvement in Bag-Frame Locks, of which the following is a full, clear, and exact description, reference being had to the accompanying drawings, which form a part of this specification.

My invention relates to locks or fasteners and more particularly to locks used on bags and the like.

The object of my invention is to provide a lock the parts of which may be readily made and reduced to a minimum number and the construction of which will render the lock inexpensive in manufacture and efficient in operation.

Having now indicated in a general way the nature and purpose of my invention, I will proceed to describe a preferred embodiment thereof with reference to the accompanying drawings, in which—

Fig. 1 is a section showing the rear view of a lock embodying my invention.

Fig. 2 is a plan view of the lock partly in section.

Figs. 3 and 4 are perspective views showing the latch and locking plate in unlocked and locked positions.

Fig. 5 is a cross-section through the lock shown in Fig. 1.

The casing *a*, the back of which is open, is provided at its ends with upwardly extending ears *b*, *b*, adapted to extend through suitable slots in the bag frame members *x*, and on being clinched over serve to secure the casing to the frame.

The front wall of the casing is slotted for the passage of hasp members *d*, *d* carried by the bag frame member *y*, and is provided with ears *e*, *e* adapted to be clinched over a top plate *f*, provided with a guide *g*, to secure it in position.

Slidably mounted within the casing is a latch *h* having a slot *n* in its front edge and provided with an upwardly extending finger piece *i* the top of which is apertured for the reception of a key and the opposite walls of which are cut out as at *j*. A key post *k* extends upwardly within the finger piece *i*. At opposite ends of the latch are downwardly extending detents *l*, *l* and ad-

jacent the ends are bolts or hasp engaging members *m*, *m* suitably bevelled toward the front. The edge of the latch adjacent the rear of the bolts is slotted as at *o*, *o*.

Beneath the latch is positioned a locking plate *c* shorter than the latch and adapted to slide transversely thereof. The locking plate is provided adjacent its ends with depressions *p*, *p*, one or the other of which is adapted to receive one of the detents *l*, *l* in either of its two normal positions. The front edge of the locking plate is provided centrally with a pair of upwardly extending ears *q* forming between them a key-engaging slot, while the rear edge of the plate is slotted as at *r*, *r*. Beneath the locking plate is positioned a bowed flat spring *s*, the ends of which bear on the bottom of the casing, while the body bears against the under side of the lock plate and maintains it in engagement with the under side of the latch. The spring also maintains the latch in latching position.

A cover plate *t*, adapted to close the rear of the casing, being held in position by means of ear *u*, *u* on the end walls of the casing, is slotted on its upper edge and provided beneath the slot with inwardly extending flanges *v*, *v*.

The lock is assembled by placing the spring in the casing with its ends against the bottom, the locking plate is placed against the under side of the latch with the slots *r*, *r* in line with the slots *o*, *o* and the latch and locking plate positioned above the spring. The top plate *f* is then placed on top of the latch and the cover plate *t* placed in position to close the rear of the casing. When the hasps *d*, *d* are entered in the lock, they will be engaged by the bolts *m*, *m*, and may be released by depressing the latch through the medium of the finger piece *i*. If it be desired to lock the lock, the key *k* is inserted into the finger piece and engages in the vertical slot in flange *q*, so that turning of the key effects a sliding of the locking plate. When the locking plate is moved, the portions of its body adjacent the edge of slots *r*, *r* are moved over flanges *v*, *v* which prevent depressing of the plate and latch. It will be obvious that the locking plate is held in unlocked position by the engagement of one of the detents *l* in one of the depressions

100

105

p, while it is held in locked position by the engagement of the other detent in its corresponding depression.

Having now fully described my invention, what I claim and desire to protect by Letters Patent is:

1. A lock of the character described comprising a casing, a slidable latch, a locking plate slidable relatively to the latch, and means independent of the latch adapted to cooperate with the locking plate to fix the latch in locking position. 10

2. A lock of the character described comprising a casing, a slidable latch, a locking plate slidable relatively to the latch, and fixed means adapted to cooperate with the locking plate to fix the latch in locking position. 15

3. A lock of the character described comprising a casing, a vertically slidable latch, a transversely slidable locking plate positioned beneath the latch, a spring bearing on the casing and on the locking plate, and fixed means carried by the casing adapted 20 to cooperate with the locking plate to fix the latch in locking position. 25

4. A lock of the character described comprising a casing, a vertically slidable latch,

a transversely slidable locking plate, cooperating means on the latch and locking plate tending to hold the locking plate in one or the other of two positions, and fixed means independent of the latch adapted to cooperate with the locking plate in one of its positions to fix the latch in locking position. 30 35

5. A lock of the character described comprising a casing open at the back, a vertically slidable latch, a locking plate slidable relative to, and positioned beneath, the latch, a spring acting between the locking plate and the casing, a cover plate for the back of the casing, and lugs carried by the cover plate adapted in one position of the locking plate to underlie said plate and fix the latch in locking position. 40 45

6. A lock of the character described comprising a casing, a slidable latch, a locking plate slidable relatively to the latch, and means fixed to a wall of the casing adapted in one position of the locking plate to cooperate with said plate to fix the lock in locking position. 50

In testimony of which invention, I have hereunto set my hand, at Philadelphia, on this 19th day of September, 1921.

JOSEPH BREZIN.
